ABSTRACT OF THE DISCLOSURE

An improved slip or gripping member that is used on well tools to lock the well tools at a desired location in a well bore. The slip is pivotally located on the well tool and is provided with wall engaging teeth on relatively opposite sides therein adjacent each end. The slip is positioned between relatively moveable abutments that are moved together to engage the ends of the slip and pivot the slip into and out of engagement with the well bore wall. One end of the slip, referred to as the active end, is provided with a plurality of spaced points or surfaces with each being arranged to engage the adjacent abutment whereby the optimum force will be exerted on the slip to move the slip teeth into holding engagement with the well bore wall. The opposite end of the slip, referred to as the passive end, is similarly provided with a plurality of points or surfaces that are arranged to engage the other abutment and are located in such a position as to cause the slip teeth to move relatively away from the well bore wall. The points or surfaces on each end of the slip are arranged to maintain a relatively constant ratio between the distance from each operative points on the active and passive ends and the adjacent well bore wall thereby permitting the predetermination of the force that is exerted on the slip during setting of the well tool.

BACKGROUND OF THE INVENTION

This invention relates generally to improved well tools and to improved slips or gripping members for use on such well tools. More particularly, but not by way of limitation, this invention relates to an improved slip of unitary construction that is pivotally mounted on the improved well tool and that is arranged to be moved by abutments on the well tool into holding engagement with the well bore wall.

This invention is an improvement to the slip or gripping member described and claimed in the U.S. Pat. No. 3,548,936, issued Dec. 22, 1970.

Packers and other well tools constructed in accordance with the disclosure of U.S. Pat. 3,548,936 have functioned satisfactorily, but certain problems have arisen due to peculiarities of the oil industry. It has long been the practice in the oil industry to manufacture tubular goods such as casing having a single nominal outside diameter in a multiplicity of inside diameters depending on the pressure or structural requirements. For example 7" nominal outside diameter casing may vary from 17 lbs. through 32 lbs. per foot in several weights with the inside diameters of the pipes varying from 6.538" to 6.094", respectively.

In accordance with this inside diameter variation, the manufacturers of oil tools generally manufacture tools for use in 7" nominal casing of several sizes or a single size tool that has the interchangeable parts of appropriate sizes. A single tool that will operate in all the various sizes will considerably reduce inventory, costs, warehousing and supply problems.

The production of a different tool to fit each size and weight of casing presents an intolerable situation in that for 7" nominal casing alone, the manufacturer must produce and stock at least six or seven different tools. In the

2

second situation, the manufacturer can, perhaps, get by with two or three different tools with several different sizes of interchangeable parts for each. Either of these solutions gives rise to the necessity for design, manufacture and warehousing of many components.

A well packer or anchor incorporating slips or gripping members constructed in accordance with this invention can, for the most part, be utilized in most casing weights for a given nominal outside diameter. Thus, one object 10 of the invention is to provide an improved well tool having an improved gripping member that can be utilized over a relatively large range of casing weights.

Another object of this invention is to provide an improved gripping for well tools wherein such tools can be utilized in a plurality of well bore diameters or casing 15 weights.

A further object of this invention is to provide an improved well tool and gripping member for such well tools that permits a substantial reduction in parts and tool inventory.

One other object of the invention is to provide an improved gripping member for well tools that is arranged whereby the setting force exerted on the gripping member can be predetermined.

SUMMARY OF THE INVENTION

In one aspect, this invention provides an improved gripping member for well tools that can be used in conduits having a preselected range of inside diameters. The 30 tool includes an elongated tool body, spaced first and second abutments moveably carried by the tool body and means for moving the abutments relatively together and apart. The improved gripping member includes a unitary body member arranged to encircle a portion of the tool body between the abutments and pivotal thereon between set and unset positions. The body member includes first and second ends engageable with the abutments to pivot the gripping member and a plurality of spaced conduit 35 engaging portions located adjacent each end and on opposite sides of the body member. Each of the conduit engaging portions is engageable with at least one of the conduits having an inside diameter within the preselected range. The unitary body member also includes a plurality of spaced surface portions located on the first end. A respective one of the surface portions engages the first abutment when a corresponding conduit engaging portion is in engagement with the conduit.

In another aspect, this invention contemplates an improved well tool for use in conduits having a preselected range of inside diameters. The improved tool comprises 50 elongated body means, spaced first and second abutment means carried on the body means, means for moving the abutments relatively toward and away from each other, and a unitary gripping member that encircles a portion of the body means between the abutment and that is pivotal relative to the body means between set and unset positions. The unitary gripping member is constructed as mentioned hereinbefore.

The foregoing and additional objects and advantages of 55 the invention will become more apparent as the following detailed description is read in conjunction with the accompanying drawing.

BRIEF DESCRIPTION OF THE DRAWING

FIGS. 1A and 1B are views, partly in cross section and partly in elevation, of an improved tool constructed in accordance with the invention. The tool is illustrated with the various components in the positions they occupy as the tool is run through the conduit.

FIGS. 2A and 2B illustrate the tool of FIGS. 1A and 1B in the set position in a well casing or conduit.

FIG. 3 is a fragmentary view of a portion of the well

tool of FIG. 1A that more clearly illustrates the construction and arrangement of the improved gripping member when the tool is set in a relatively lightweight conduit.

FIG. 4 is a view similar to FIG. 3, but illustrates the improved gripping member set in a heavier weight conduit having the same nominal outside diameter.

FIG. 5 is another view similar to FIG. 3 but illustrating the improved gripping member set in still a heavier weight conduit having the same nominal outside diameter.

DETAILED DESCRIPTION OF THE PREFERRED EMBODIMENT

Referring to the drawing and to FIGS. 1A and 1B in particular, shown therein is an improved well tool generally designated by the reference character 10. The well tool 10 includes an elongated tool body 12 that is comprised of a plurality of components that are threadedly connected to facilitate the manufacture of the tool body 12. At its upper end, the tool body 12 is provided with a thread 14 for connecting the tool 10 with tubing (not shown) that is used to run the well tool 10 into a well bore. At its lower end, the tool body 12 is also provided with threads 16 that may be utilized to connect additional tools or other apparatus to the lower end of the well tool 10. Mounted on the exterior of the tool body 12 is a housing 18 that extends coaxially along a portion of the tool body 12 and terminates at its lower end in an inwardly extending flange 20 forming a downwardly facing abutment 22.

A slip or gripping member sleeve 24 encircles a portion of the tool body 12 in sliding relationship thereto. The slip sleeve 24 is provided with an outwardly extending annular flange 26 that is arranged to engage the flange 20 on the housing 18 for purposes that will become more apparent hereinafter. A lug 27 on the sleeve 24 is arranged to engage surface 29 on the gripping member 30 to exert an unsetting force on the gripping member 30 during release of the tool 10. Disposed within the housing 18 is a helical compression spring 28 that has its upper end engaging the tool body 12 and its lower end engaging the flange 26 on the slip sleeve 24. The slip sleeve 24 extends through a unitary gripping member 30 that is arranged for pivotal movement on the tool body 12 and the slip sleeve 24.

The gripping member 30 is provided with an upper or passive end 32 that is engageable with the abutment 22. The configuration of the upper end 32 will be described in detail hereinafter in connection with a discussion of FIGS. 3 through 5. The gripping member 30 also includes upper wall engaging portion 34 and a lower wall engaging portion 36. A spring 38 mounted on the gripping member 30 has one end in engagement with the slip sleeve 24 to bias the gripping member 30 toward the retracted position as illustrated in FIG. 1A. The gripping member 30 also includes a lower or active end 40 that is engageable with an upwardly facing abutment 42 that comprises a portion of an upper packer thimble 44. The lower end 40 and the wall engaging portions of the gripping member 30 will also be described more fully in connection with FIGS. 3 through 5.

The upper packer thimble 44 slidably encircles the tool body 12 below the gripping member 30 and includes a lower abutment 46 that is in engagement with the uppermost of a plurality of resilient packing rings 48. The lowermost of the packing rings 48 is in engagement with an annular abutment 50 that forms the upper end of a lower packer thimble 52. The lower packer thimble 52 is also slidably disposed on the tool body 12 and terminates at its lower end in a downwardly facing abutment 54.

A lower slip sleeve 56 slidably encircles the tool body 12 and has an outwardly extending annular flange 58 on its upper end that is disposed within and engages the interior of the lower thimble 52. The slip sleeve 56 ex-

tends through a lower gripping member 60 that is constructed similar to the gripping member 30 except that it is inverted on the well tool 10. The gripping member 60 includes springs 62 that have one end in engagement with the slip sleeve 56 to aid in urging the gripping member 60 toward the retracted position as illustrated in FIG. 1B. The gripping member 60 includes an upper or active end 64 and a lower or passive end 66. The upper end 64 is engageable with the abutment 54 while the lower end 66 is engageable with and upwardly facing abutment 68 on a drag block assembly 70. The upper and lower ends 64 and 66 of the lower gripping member 60 are also constructed as will be described in connection with the gripping member 30 which is illustrated in FIGS. 3 through 5.

The lower end of the slip sleeve 56 is formed into an exterior flange 72 that is disposed within the drag block assembly 70. As constructed, the drag block 70 is moveably positioned on the tool body 12 for both their rotational and longitudinal movement. Such movement is controlled by a shear pin 74 that operates within a J-slot 76 formed in the tool body 12.

Between the abutment 68 formed on the drag block assembly 70 and the shear pin 74, a plurality of spring loaded drag blocks 78 are located in openings in the body of the drag block assembly. The drag blocks 78 are arranged to frictionally engage the interior wall of the conduit or casing 80 (see FIG. 2B) as the well tool 10 travels therethrough so that relative movement can be accomplished between various moveable components of the tool 10 as is well known in the oil tool art.

Referring to FIGS. 2A and 2B, the well tool 10 is shown therein in the set position in a casing 80, which will normally be disposed in a well bore (not shown). Upon reaching the desired position in the well bore for setting the well tool 10, a tubing (not shown) connected to the upper end of the tool is rotated to the right and lowered so that the J-slot 76 formed in the tool body 12 moves downwardly with respect to the shear pin 74 that is mounted in the drag block assembly 70. Due to the frictional engagement of the drag blocks 78 with the conduit 80, the drag block assembly 70 and the lower gripping member 60 remain in a relatively fixed position.

The upper gripping member 30, the upper thimble 44, the packing rings 48, and the lower thimble 52 move downwardly with the tool body 12. The downward movement brings the downwardly facing abutment 54 into engagement with the upper or active end 64 of the lower gripping member 60, causing the lower gripping member 60 to rotate into the set position as illustrated in FIG. 2B. As illustrated in FIG. 2A, the upper gripping member 30 has also moved relatively downwardly with its lower or active end 40 in engagement with the upwardly facing abutment 42 on the upper thimble 44. The upper gripping member 30 is rotated toward the set position, but is not firmly set.

Additional downward movement of the tool body 12 exerts a force through the spring 28 and the upper slip sleeve 24 on the upper thimble 44, deforming the packing rings 48 outwardly into sealing engagement with the conduit 80. Simultaneously, the upper gripping member 30 has, in a manner of speaking, ratcheted downwardly in the conduit 80 under the influence of the downwardly facing abutment 22 on the housing 18 which is in engagement with the passive end 32 of the upper gripping member 30. When the packing elements 48 are fully deformed, further downward movement of the upper thimble 44 is prevented, and the full force of the tubing is exerted on the upper gripping member 30.

Since the lower gripping member 60 is in engagement with the casing 80 and fully set and the downwardly facing abutment 22 on the housing 18 is in engagement with the passive upper end 32 of the upper gripping member 30, the force exerted on the upper gripping member 30 to cause the setting thereof and deformation of the packing

ring 48 is determined by the difference in the lever arms or couples acting on the gripping member.

As can be seen more clearly in FIGS. 3, 4 and 5, the upper or passive end 32 of the gripping member 30 and, similarly, lower end 66 of the lower gripping member 60 are provided with discrete abutment engaging portions 32a, 32b and 32c. The lower or active end 40 of the gripping member 30 is also provided with discrete abutment engaging portions 40a, 40b and 40c. Similarly, the upper end 64 of the lower gripping member 60 will be provided with such contact engaging portions.

In addition, the active end 40 of the upper gripping member 30 is provided with a contact or "set-out" portion 41 near the periphery thereof and adjacent the wall engaging portion 36. The set-out portion is located to provide an initial contact point with the abutment 42 that has maximum torque upon engagement to quickly and easily initiate the pivotal movement of the gripping member 30 toward its set position.

The lever arms previously referred to are identified in FIG. 3 as A-1 and A-2, in FIG. 4 as B-1 and B-2, and in FIG. 5 as C-1 and C-2. The lever arms are created due to the engagement of the teeth or conduit engaging portions adjacent the passive ends of the gripping members 30 and 60. The provision of the discrete contact portions on the active and passive ends of the gripping members and, thus, the control of the length of the lever arms permits the predetermination of the force that will be exerted in setting the gripping members.

For example, if the well tool 10 is to be set in a conduit having a thin wall such as illustrated as being the casing 80a, the lever arm A-1 is the distance from the wall of the conduit 80a to the contact portion 32a on the gripping member 30 which is in engagement with the downwardly facing abutment 22 on the housing 18. The lever arm A-2 extends from the wall of the conduit 80a to the contact portion 40a which is in engagement with the upwardly facing abutment 42 on the upper thimble 44. Since the setting force on the gripping member 30 is determined by the difference in the lever arms A-1 and A-2, it is possible to select the locations of the contact portions 32a and 40a so that the desired force is exerted on the gripping member 30.

As mentioned earlier, one object of this invention is to provide an improved well tool 10 and an improved gripping member that can be utilized in conduits having varying inside diameters. Accordingly, FIG. 4 illustrates the gripping member 30 in the set position in a conduit 80b which has the same nominal outside diameter as the conduit 80a but has a smaller inside diameter. In order for the well tool 10 to be successfully set in the conduit 80b, the gripping member 30 has been constructed so that the lever arms B-1 and B-2 have substantially the same ratio as did the lever arms A-1 and A-2 with the gripping member 30 set in the conduit 80a. In view of this, and even though the well tool 10 is being run in conduit 80b which has a different inside diameter than the conduit 80a, the forces on the gripping member 30 can be controlled so that the same setting force is attained.

As a further illustration of the versatility of the invention, FIG. 5 illustrates the gripping member 30 set in a conduit 80c having still a smaller inside diameter than did the conduit 80b. In this instance, the contact portions 32c and 40c are in engagement with the downwardly facing abutment 22 and the upwardly facing abutment 42, respectively, providing lever arms C-1 and C-2 that have the same ratio or substantially the same ratio as did the lever arms A-1, A-2 and B-1, B-2. Thus, it can be readily appreciated that the setting force exerted on the gripping member 30 in the casing 80c will be substantially the same as that on the gripping member 30 when set in the casing 80a or 80b.

It should also be pointed out that the wall engaging portion 36 and similarly the wall engaging portion 34 on the gripping member 30 are provided with arcuate configurations. The wall engaging portions are roughly di-

vided into wall engaging portions 36a, 36b and 36c as illustrated in FIG. 3. Although there may be some overlap in the wall engaging portions, it can be seen that the wall engaging portion 36a is in secure holding engagement with the conduit 80a as shown in FIG. 3, the wall engaging portion 36b is in secure holding engagement with the conduit 80b as shown in FIG. 4, and the wall engaging portion 36c is in secure holding engagement with the conduit 80c as illustrated in FIG. 5. It can be further seen that there is a relationship established between the respective abutment engaging portions 32a, 40a and the wall portion 36a; the abutment engaging portions 32b, 40b and the wall engaging portion 36b; and, the abutment engaging portions 32c, 40c and the wall engaging portion 36c. Furthermore, this relationship provides appropriate lever arms whereby the setting force to be exerted on the gripping member 30 is substantially the same regardless of the inner diameter of the conduit 80. As previously mentioned, the well tool 10 can then be utilized throughout the varying inner diameters of conduit 80 which have a single nominal size or diameter.

The ability to perform in such varying inside diameters with the well tool 10, permits the manufacturer to utilize a single tool and, thus, reduces his inventory parts and reduces the manufacturing and design problems to the very minimum.

The well tool 10 illustrated is a retrievable tool, that is, the well tool can be unset and removed from the conduit 80 when desired. Retrieval is accomplished by rotating the tubing (not shown) and the tool body 12 to the right and raising the tubing and tool body. As the tool body 12 rotates, the shear pin 74 moves into a portion of the J-slot 76 that permits the tool body 12 to be moved upwardly relative to the drag block assembly 70.

As the tool body 12 is raised, the flange 20 on the lower end of the housing 18 engages an exterior flange 26 on the upper slip sleeve 24. This engagement moves the upper slip sleeve 24 relatively upwardly bringing the abutment 27 thereon into engagement with the surface 29 on the upper gripping member 30. Continued upward movement of the tool body 12 and the slip sleeve 24 exerts a force on the upper gripping member 30 lifting and rotating the gripping member 30 to the retracted position illustrated in FIG. 1A.

Release of the upper gripping member 30 permits the upper thimble 44 to move upwardly, releasing the deforming pressure on the packing rings 48 which return to the position illustrated in FIG. 1A. As the tool body 12 is pulled upwardly, the upper thimble 44 is pulled upwardly therby and also pulls the lower thimble 52 upwardly, moving the downwardly facing abutment 54 out of engagement with the upper or active end 64 of the lower gripping member 60. When this occurs, the springs 62 carried by the lower gripping member 60 pivot the gripping member 60 into the retracted position illustrated in FIG. 2A.

In the event that the lower gripping member 60 does not release, the lower slip sleeve 56, which is pulled upwardly by the lower thimble 52, pulls the drag block assembly 70 moving the upwardly facing abutment 68 thereon into engagement with the lower or passive end 66 of the lower gripping member 60. This engagement exerts a positive force on the lower gripping member 60, rotating the member 60 into the retracted or unset position. As soon as the lower gripping member 60 has been released, the entire well tool 10 is in the position illustrated in FIGS. 1A and 1B and is in condition to be removed from the well bore.

It will be understood that the foregoing detailed description of the preferred embodiment is presented by way of example only and that many changes and modifications can be made thereto without departing from the spirit and scope of the invention.

The embodiments of an invention in which an exclusive property or privilege is claimed are defined as follows:

1. An improved gripping member for well tools that are useful in conduits having a preselected range of inside diameters, the tool including an elongated tool body

spaced first and second abutments movably carried by the tool body and means for moving the abutments relatively together, said gripping member comprising:

a unitary body member arranged to encircle a portion of the tool body between the abutments and pivotal relative thereto between set and unset positions, said body member having

first and second ends engageable with the abutments to pivot said gripping member,

a plurality of spaced conduit engaging portions located adjacent each said end on opposite sides of said body member, each said conduit engaging portion being engageable with at least one of said conduits having an inside diameter within the preselected range, and

a plurality of spaced surface portions located on said first end, one of said surface portions engaging said first abutment when a respective conduit engaging portion is in engagement with one of the conduits within the preselected range of inside diameters.

2. The improved gripping member of claim 1 and also including:

a plurality of spaced surface portions located on said second end, the surface portions on said second end being located to pivot said gripping member toward the unset portion when in engagement with the second abutment; and

wherein the surface portions on said first end are located to pivot said gripping member toward the set position when in engagement with the first abutment.

3. The improvement gripping member of claim 2 wherein said surface portions are located on said gripping member with a substantially constant ratio between the distances from each of the conduits to a respective surface portion on said first end to a respective surface portion on said second end when said gripping member is disposed in any conduit having an inside diameter within the preselected range.

4. An improved well tool for use in conduits having a preselected range of inside diameters, said tool comprising:

elongated body means having a longitudinal axis; spaced first and second abutment means carried by said body means;

means for moving said first and second abutment means relatively toward and away from each other; and a unitary gripping member encircling a portion of said body means between said abutment means and pivotal relative to said body means between set and unset positions, said gripping member having

first and second ends engageable with said first and second abutment means, respectively, to pivot said gripping member,

a plurality of spaced conduit engaging portions located adjacent each said end and on opposite sides of said gripping member, each said conduit engaging portion being engageable with at least one of said conduits having an inside diameter within the preselected range, and

a plurality of spaced surface portions located on said first end, one of surface portions engaging said first abutment means when a respective conduit engaging portion is in engagement with one of said conduits within the preselected range of inside diameters.

5. The improved well tool of claim 4 and also including a plurality of spaced surface portions on said second end located to pivot said gripping member toward the unset position, one of the surface portions on said second end being engageable with said second abutment means when a respective one of the surface portions on said first end is in engagement with said first abutment means.

6. The improved well tool of claim 5 wherein the surface portions on said first and second ends are located on said gripping member at positions to maintain the

ratio substantially constant between the distances from each of the conduits within the preselected range to the respective surface portion on said first end and to the respective surface portion on said second end.

5 7. The improved well tool of claim 6 and also including:

third abutment means carried by said body means; packing means encircling a portion of said body means between said first and third abutment means, said packing means being deformable to form a seal between said body means and the conduit; and said means for causing relative movement of said first and second abutment means also includes means for moving said first and third abutment means toward and away from each other to deform and to release said packing means.

8. The improved well tool of claim 7 wherein said means for causing relative movement of said first and third abutment means includes:

a fourth abutment means carried by said body means; a second gripping member pivotal with respect to said body means between set and unset positions and located on said body means between said third and fourth abutment means, said second gripping member having first and second ends with a plurality of spaced surface portions on said first end located for engagement with said third abutment means in respective set positions of said second gripping member and with at least one surface portion on the second end of said second end arranged to engage said fourth abutment means to pivot said second gripping member toward the unset position.

9. An improved gripping member for well tools that are useful in conduits having a preselected range of inside diameters, the tool including an elongated tool body, spaced first and second abutments movably carried by the tool body and means for moving the abutments relatively together, said gripping member comprising:

a unitary body member arranged to encircle a portion of the tool body between the abutments and pivotal relative thereto between set and unset positions, said body member having

first and second ends engageable with the abutments to pivot said gripping member,

a plurality of spaced conduit engaging portions located adjacent each said end on opposite sides of said body member, each said conduit engaging portion being engageable with at least one of said conduits having an inside diameter within the preselected range, and

a contact portion on said first end located proximate the conduit engaging portion adjacent said first end and engageable with the first abutment to initiate pivotal movement of said gripping member to the set position.

10. The improved gripping member of claim 9 and also including:

a plurality of spaced surface portions located on said first end, one of said surface portions engaging said first abutment when a respective conduit engaging portion is in engagement with one of the conduits within the preselected range of inside diameters.
